ETIENNE CHALLET, OF GENEVA, SWITZERLAND, ASSIGNOR TO MAURICE ARTHUR BOREL, OF PONTARLIER, FRANCE.

METHOD OF MANUFACTURE OF RECTANGULAR TUBES.

Application filed July 14, 1927, Serial No. 205,795, and in Switzerland June 11, 1927.

Tubes of rectangular section have already been manufactured by drawing, starting for example with a tube of circular cross section. It is very easy to obtain in this way 5 tubes in which the wall has everywhere the same thickness, that is to say in which the angles are rounded; it is, on the other hand, much more difficult to obtain a tube with sharp angles, that is to say having at the 10 corners a much greater thickness than over the remainder of the periphery; in order to obtain this result the following procedure is usually adopted; a tube with rounded angles is drawn which is thicker than the sharp 15 angled tube to be obtained and, for example by grinding or milling, it is reduced to the desired thickness at the same time as the angles are formed. This mode of operation presents the disadvantage that there 20 is a complete thinning operation to be performed by grinding or milling; in addition this reduction in thickness removes the outer metal layer, which layer is of great use because the cold working has increased its 25 strength. The tube blank may also be passed immediately through an exactly rectangular draw plate, but this blank must then be a little larger than the finished tube 30 in order to provide the necessary material to fill up the angles. Now this is difficult to effect because as the amount of material in question is very small it is difficult to 35 judge it exactly; usually too much will be allowed, the effect of which is to make the sides of the tube slightly concave. If a 40 mandrel is placed inside the tube in order to prevent this deformation the surplus material will be pressed into the angles of the drawplate in excess and will cause these angles to be torn off.

The object of the invention is to provide a method of making rectangular metal tubes having plane surfaces and sharp angles. The method according to this invention consists in passing a tube blank through a draw plate having an orifice of substantially rectangular cross section and being provided with small chambers for the escapement of surplus material, thereby preventing the 45 surplus material from producing a deformation of the tube walls, and then removing the surplus material.

Referring to the accompanying drawing, Fig. 1 is a fragmentary end view of a finished rectangular pipe. Fig. 2 is a plan

view of a draw plate used in the method for making rectangular pipes according to this invention. Figs. 3 and 4 are fragmentary end views of a pipe at different stages during the manufacturing process.

4 is a drawplate the drawing orifice in which is of rectangular cross section and is formed by a rectangle 5 extended at each angle in small escapement chambers 6. The tube blank which has to pass through the 60 drawplate is somewhat larger than the tube produced from the latter, the surplus material being free to expand into the chambers 6 filling them to a varying extent according to the thickness of the blank. It 65 will thus be possible to obtain correct tubes even if this thickness varies somewhat. The burrs 7 (see Fig. 3) produced upon the tube issuing from the drawplate by the chambers 6 are easily removed, for example by grinding or milling. The tube with its burrs could also be first passed through a rolling mill which would make the burrs occupy the position shown in Fig. 4, and these burrs 70 be removed afterwards, for example by 75 grinding.

The tubes manufactured in this way have sharp angles, so that they are adapted for use as rules for example, or for the rods of sliding calipers, etc., for which uses the rectangular tubes with rounded corners would 80 not be suitable.

I claim:

1. The method of making rectangular metal tubes with plane surfaces and sharp 90 angles, which consists in passing a tube blank through a draw plate having an orifice of substantially rectangular cross section and being provided with small chambers for the escapement of surplus material, thereby 95 preventing the surplus material from producing a deformation of the tube walls, and then removing this surplus material.

2. The method of making rectangular metal tubes having plane surfaces and sharp 100 angles, which consists in passing a tube blank through a draw plate having an orifice of substantially rectangular cross section, the corners of the rectangle extending into small chambers for the escapement of surplus material, thereby preventing the surplus material from producing a deformation of the tube walls, and then removing this surplus 105 material.

3. The method of making rectangular 110

metal tubes having plane surfaces and sharp angles, which consists in passing a tube blank through a draw plate having an orifice of substantially rectangular cross section, the corners of the rectangle extending into small chambers for the escapement of surplus material, thereby preventing the surplus mate-

rial from producing a deformation of the tube walls, passing the drawn tube through a rolling mill to press down the burrs produced by the escapement chambers, and then removing the burrs by mechanical means. ¹⁰

In testimony whereof I affix my signature.
ETIENNE CHALLET.
